[57] CLAIM

The ornamental design for a folding chair, as shown and described.

DESCRIPTION

FIG. 1 is a perspective view of the folding chair having a

handle with a flat instrument incorporated therein;

FIG. 2 is a front view of the folding chair shown in FIG. 1;

FIG. 3 is a rear view of the folding chair shown in FIG. 1;

FIG. 4 is a side view of the folding chair as seen from the right side of FIG. 2;

FIG. 5 is a side view of the folding chair as seen from the left side of FIG. 2;

FIG. 6 is a top view of the folding chair shown in FIG. 2; and

FIG. 7 is a bottom view of the folding chair shown in FIG. 2;

FIG. 8 is a perspective view of a second embodiment of the folding chair having a handle with a spherically protruding instrument incorporated therein;

FIG. 9 is a front view of the folding chair shown in FIG. 8;

FIG. 10 is a rear view of the folding chair shown in FIG. 8;

FIG. 11 is a side view of the folding chair as seen from the right side of FIG. 9;

FIG. 12 is a side view of the folding chair as seen from the left side of FIG. 9;

FIG. 13 is a top view of the folding chair shown in FIG. 9; and,

FIG. 14 is a bottom view of the folding chair shown in FIG. 9.
